CONVERTIBLE CHAIR

Elenora B. Lehman and Edgar A. Lehman,
Elkhart, Ind.

Application March 5, 1947, Serial No. 732,630

5 Claims. (Cl. 155—127)

1

This invention is concerned with improvements in chair constructions.

It is an object of the invention to provide a chair, having the general appearance and characteristics of a child's high chair, including a tray member, tray supporting arms and a footrest, which is so constructed that the tray member, the supporting arms and the footrest may be readily detached and removed therefrom whereby to convert the chair into a youth's chair or a stool.

It is another object of the invention to provide improvements in a chair construction of the type having a leg supported horizontal seat, an upright back, horizontal forwardly extending arms and a tray supported on said arms.

It is a further object of the invention to provide a chair of the type described having improved means for detachably and adjustably mounting thereon a tray member whereby the tray member may be connected to an arm on one side of the chair for horizontal swinging movement and adjustably secured in any desired position to the arm on the opposite side of the chair.

It is another object of the invention to provide in a chair construction of the type described a one-piece removable member having arm forming end portions extending forwardly in a horizontal plane above the seat of the chair and having an intermediate portion extending around the back of the chair and means for detachably connecting the arm forming portions to the seat and the intermediate portion to the back of the chair.

It is another object of the invention to provide improved means for connecting a footrest to a chair of the type described whereby it may be readily detached therefrom.

These and other objects will be apparent from a description of the chair which is shown, by way of example, in the accompanying drawings, wherein:

Fig. 1 is a plan view of a chair embodying the principles of the invention;

Fig. 2 is a front elevation of the chair;

Fig. 3 is a side elevation of the chair;

Fig. 3a is a partial detailed section taken on the line 3a—3a of Fig. 2, to an enlarged scale;

Fig. 4 is a detail view of the tray latching mechanism;

Fig. 5 is a section, taken on the line 5—5 of Fig. 4;

Fig. 6 is a fragmentary detail bottom plan view, to an enlarged scale, of the latching mech-

anism;

Fig. 7 is a fragmentary detail bottom plan view, to an enlarged scale, of the tray pivot mechanism;

Fig. 8 is a plan view of a chair showing a modified form of tray latching mechanism;

Fig. 9 is a fragmentary detail bottom plan view, to an enlarged scale, of the modified form of tray latching mechanism; and

Fig. 10 is a side elevation of the latch mechanism of Fig. 8.

Referring to Figs. 1 to 6 of the drawings, the preferred form of the invention comprises a chair having a substantially round horizontal seat forming member 10 supported on four legs 11

15 which may be round or any other suitable cross section. The legs 11 are slanted outwardly for greater stability and connected by a brace member 12 which is preferably substantially circular in form and positioned intermediate the seat 10 and the bottom ends of the legs 11.

A back forming member 13 extends upwardly from the rear side of the seat 10. The back 13 is transversely curved to conform generally to the periphery of the seat 10 to which it is secured at its bottom edge 14 by any conventional securing means such as screws or the like. The vertical sides and the top of the back 13 are curved to enhance the appearance and a relatively short rounded reinforcing member 15 is provided on the top edge.

A generally C-shaped one-piece arm forming member 16 is provided having end portions 17 and 18 which constitute forwardly projecting tray-supporting side arm members and an intermediate portion 19 which is adapted to extend around the rear side of the back 13. The intermediate portion 19 is detachably secured to the back 13 by a U-shaped bracket member 20 having its right portion 21 secured to the back 13

40 by means of rivets 22 or equivalent securing means and its leg portions 23 extending rearwardly. The leg portions 23 of the member 20 are provided with aligned apertures which receive a tapered securing pin 24 having a ring 25

45 by means of which it may be grasped for removal. The intermediate portion 19 of the arm forming member 16 is provided with a cooperating aperture which may be aligned with the apertures in the legs 23 of the bracket member to receive the pin 24 when in assembled relation.

Generally vertical brace members 26 are provided adjacent the forward ends of the arms 17 and 18. The brace members 26 have bent over ends to form upper flanges 27 which are secured in any appropriate manner to the bottom side of the arms 17 and 18 and lower flanges 28 which

are detachably secured beneath the seat 10 by means of stud bolts 29 provided with wing nuts 30. The brace members 26 slope outwardly and upwardly and support the arms 17 and 18 of the chair.

A tray member 31 which is preferably kidney-shaped is provided for detachable positioning on the arms 17 and 18. The tray 31 is provided adjacent its rear corner 32 with a downwardly extending pivot bolt or stud 33. The stud 33 is preferably provided with a base plate 34 which is permanently secured to the tray by screws 35 or in any similar manner.

The arm member 17 is provided with a plurality of spaced sockets 36 formed in part by aligned apertures in the top and bottom legs 37 of a generally U-shaped clip member 38 secured on the arm 17 by the bolt 39. The arm 18 is provided with apertures which are in alignment with the respective holes in the legs 37 and co-operate therewith to form the sockets 36. Each socket 36 is provided with a groove or slot 40 in one side and the pivot bolt 33 is provided with a cross pin 41 extending at one side near its end. The groove 40 and cross pin 41 are so arranged that, to permit removal of the pivot bolt 33 from a socket 36, the tray 31 must be swung to a left, or fully opened position, in order to align the pin 41 with the groove 40. The groove 40 is of a size sufficient to permit free passage of the extending end of the pin 41, thus permitting the removal of the pivot bolt 33 from the socket 36. This construction not only permits the removal of the entire tray 31 as a unit but it also permits the pivot point of the tray 31 to be adjusted towards and away from the back 13 in order to accommodate children of different size and to position the tray as closely as desirable to the child.

The opposite side 42 of the tray 31 and the arm 18 are provided with cooperating latch elements for securing or latching the tray 31 in the desired position. As illustrated more particularly in Figs. 4, 5 and 6, the arm 18 is provided with a U-shaped channel member 43 along its outer edge which is secured by means of screws 44 in a recess 45 provided in the edge of the arm.

The tray 31 is provided on its underside with a generally U-shaped bracket having its bight portion 46 secured to the tray 31 by screws 47. The legs 48 of the U-shaped bracket are provided with aligned apertures 49 to receive one leg of an L-shaped latch member 50 which is retained on the legs 48 of the U-shaped bracket by a cross pin 51. A cam 52 is provided on the inner end of the latch member 50 which cooperates with the channel member 43 to secure the tray 31 to the arm 18 when the latch member 50 is rotated by grasping the knob or handle 53 and turning the same in the proper direction. The latch mechanism is constructed so that the cam 52 on the latch member 50 will engage in the channel 43 in locking relation regardless of the particular socket 36 in which the pivot bolt 33 is positioned.

A footrest 54 is provided for positioning on the forward legs 11. The footrest 54 consists of a cross bar 55 and a base member 56. The forward legs 11 are provided with pivot sockets 57 for receiving pivot pins 58 and 59 on the footrest. The pin 58 is rigidly secured to the base 56 while pin 59 is positioned in a socket 60 in the base 56 and urged into projecting position by a spring 61. With this construction the pin 59 may be retracted to remove it from the socket 57 after

which the entire footrest 54 may be removed by withdrawing the pin 58 from the other socket 57. The footrest 54 is provided with a rearwardly projecting brace member 62 having a series of slots 63 along the bottom edge which are adapted to engage a supporting bar 64 positioned between the forward legs 11 to provide adjustable positioning of the footrest.

A modified form of tray latching mechanism is illustrated in Figs. 8, 9 and 10. The tray 70 is pivotally mounted on the arm 71 in the same manner as in Figs. 1 to 4. The arm 72 is provided with a latch member or plate 73 which is secured in a recess 74 provided in the outer edge of the arm. The member 73 is provided with a plurality of socket formations 75 adapted to receive the end 76 of a latching pin 77. The pin 77 is secured to the underside of the tray 70 by means of a U-shaped bracket 78 having a base portion 79 and legs 80 which are provided with aligned apertures 81. The latching pin 77 is received in sliding relation in the apertures 81. A spring 82 is provided on the pin 77 with one end abutting a leg 80 of the bracket 78 and the other end engaging a transverse pin 83 in the latch pin 77. The spring 82 tends to urge the latch pin 77 in the inward direction. The latch pin 77 is provided with a head 84 which may be grasped to withdraw the end 76 of the pin from the socket 75. This construction provides for a plurality of spaced points at which the tray 70 may be latched in position.

The major portion of the chair is preferably made of wood. The elements provided for connecting the arm forming member to the back, for pivoting the tray, and for latching the same to the arm members, are preferably of metal. The brace members 26 are also preferably of metal. However, it is contemplated that other suitable materials may be utilized for the various parts of the chair.

While specific details of construction have been referred to in describing the illustrated form of the invention, it will be understood that other details of construction may be resorted to within the spirit of the invention.

We claim:

1. A convertible chair comprising a seat forming member and a generally upright back forming member, a one-piece generally C-shaped member having end portions extending forwardly of said back forming member and providing tray supporting arms, said arms extending horizontally along the sides of and in vertically spaced relation above the seat member, said C-shaped member having an intermediate portion extending between the arm forming end portions and positioned around the rear of the back, means readily detachably securing said intermediate portion to said back, generally upright brace members extending from the seat member to forward portions of said arms, and means readily detachably connecting said brace members to the bottom of said seat member.

2. In a chair construction comprising a seat forming member, a back forming member, a horizontally positioned member having side arm forming portions extending forwardly of said back forming member above said seat forming member and a removable and adjustable tray member, one of said arm forming portions being provided with a plurality of sockets arranged in spaced relation forwardly of said back forming member and said tray having thereon a pivot means adapted to be selectively positioned in said

sockets, a latch means on said tray and the other of said arm portions, said latch means comprising a plurality of socket formations on said arm portion and a cooperating spring-pressed retractable plunger member on said tray opposite said pivot means, whereby said tray may be secured in latched position irrespective of the socket in which said pivot means is positioned.

3. In a chair construction as claimed in claim 2, and means on said pivot means preventing removal of said pivot means from said socket until said tray has been moved to a fully opened position.

4. A convertible high chair comprising a generally circular seat forming member, supporting legs depending from said seat member, a forwardly curved back member extending upright from the rear of said seat member, a one-piece generally C-shaped member having tray supporting arms extending forwardly of said back member above said seat forming member and an intermediate connecting portion readily detachably connected to said back member, upright forward brace members connected to said arms and readily detachably connected to said seat member, a tray member detachably pivotally connected to one of said arms, the pivotal connection of said tray member being at a selected one of spaced pivoting points along said arm, and interengaging latch means connecting said tray and the other of said arms, the latch connection being at a selected one of spaced connecting points along said other arm, whereby said tray may be selectively positioned on said arms and said tray and its supporting arms may be readily detached from said chair to convert the same

10
15
20
25

6 to an armless chair suitable for use as a youth's chair.

5. In a chair construction comprising a seat forming member, a back forming member and a horizontally positioned member having forwardly extending side arm forming portions in vertically spaced relation above said seat forming member, a removable and adjustable tray member supported on said arms, one of said arms being provided with a plurality of spaced sockets and said tray having thereon a pivot means adapted to be selectively positioned in said sockets, said tray and the other of the arms on said arm forming member being provided with a latch means comprising a channel member on said arm and a pivotally mounted cam member on said tray whereby said tray may be secured in latched position irrespective of the socket in which said pivot means is positioned.
